UNITED STATES PATENT OFFICE.

SIMON G. PETTERSON, OF PINE BLUFF, ARKANSAS.

HOOP-ROLLER.

No. 904,220.

Specification of Letters Patent.

Patented Nov. 17, 1908.

Application filed October 30, 1907. Serial No. 399,880.

To all whom it may concern:

Be it known that I, SIMON G. PETTERSON, a citizen of the United States, residing at Pine Bluff, in the county of Jefferson, State 5 of Arkansas, have invented certain new and useful Improvements in Hoop-Rollers; and I do hereby declare the following to be a full, clear, and exact description of the invention, such as will enable others skilled 10 in the art to which it appertains to make and use the same.

This invention has relation to devices for trundling or rolling and guiding hoops.

It is the object of the invention to provide 15 a hoop roller so constructed that a child can run at the side of the hoop as though batting it along in the usual way, and have the trundling means guide and control it without the exercise of great skill.

20 It is also the object of the invention to provide a trundling device so constructed that the child need not run behind in the path of the hoop so that if the latter should fall the child may not fall over it and be 25 hurt.

To the foregoing ends the invention consists of a hoop-roller comprising a length of stiff wire bent to form an eye or loop in the end and another a short distance therefrom 30 positioned approximately in line therewith the connections between the two eyes consisting of portions of lengths of wire, and the latter being bent together below the second-mentioned loop to form a handle or the support port for a handle.

The drawing hereto annexed shows an embodiment of the invention, and constitutes, with the reference characters marked thereon, a part of this specification, the said 40 drawing being a side view of the invention in the position it will occupy when applied to use.

In carrying out my invention I provide a hoop of round or it may be flattened wire 45 suitable for a child to roll about in its play. Instead of batting the hoop about, a thing which requires considerable skill, my trundling device consists of a roller or trundler comprising a handle 2 extending laterally 50 from the hoop 1 and having an eye or loop 3 at the end of the handle and another loop or eye 4 extending forward of the eye 3 and in substantial alinement therewith, the two eyes being joined by connecting means 5 on

the side of the hoop opposite to that from 55 which the handle extends.

In making this trundling device I prefer to form it from a length of stiff wire bending it so as to form the eye 4 and then doubling the extended parts 6 upon themselves so as to constitute the connecting means 5 between the eye 4 and the eye 3 which is formed by bending the lengths of wire in opposite directions and at substantially a right angle to the connecting part 5. 60 After forming the eye 3 as stated the balance of the wire is doubled upon itself and extends outwardly at substantially a right angle to the hoop when standing upright and is made to constitute the handle of the 70 trundling device by which the hoop is manipulated. If desired the wire handle specified may have a wooden handle placed thereon as is indicated in dotted lines in the figure. 75

With the invention specified a child not skilled in the rolling of a hoop can readily learn to trundle a hoop about in a way closely simulating that of batting on its sides instead of pushing it from the rear with 80 danger of falling over it if the hoop should fall. Aside from this the manner of constructing the trundling device herein described, it is one that makes sure of running the hoop easily without danger of the 85 child falling over it, it being understood that the eyes or loops through which the hoop passes are much larger than the diameter of the hoop itself. 90

What is claimed is—

A rolling device for hoops composed of a single piece of wire bent upon itself intermediate its ends and the sides closely engaged except at two points where the sides are distended into eyes spaced apart, the 95 terminals of said sides adapted to receive a handle and with one of said eyes in alinement with the longitudinal plane of the handle receiving portion and the other of said eyes inclined to the longitudinal plane of 100 the handle receiving portion, said eyes adapted to be permanently engaged with a hoop.

In testimony whereof, I affix my signature, in presence of two witnesses.

SIMON G. PETTERSON.
